UNITED STATES PATENT OFFICE.

THEODORE SCHERF, OF CLEVELAND, OHIO.

APPARATUS FOR SOFTENING PAPER.

No. 905,465.

Specification of Letters Patent. Patented Dec. 1, 1908.

Application filed May 2, 1908. Serial No. 430,494.

To all whom it may concern:

Be it known that I, THEODORE SCHERF, a citizen of the United States, residing at Cleveland, in the county of Cuyahoga and State of Ohio, have invented a certain new and useful Improvement in Apparatus for Softening Paper, of which the following is a full, clear, and exact description, reference being had to the accompanying drawings.

10 This invention relates to apparatus for softening paper, and more particularly to an apparatus of the type disclosed in my former patents No. 860,696 issued July 23, 1907, and 873,169 issued December 10, 1907.

15 As has been pointed out in connection with the apparatus disclosed in the aforesaid patents, paper which is pliable and soft as well as strong possesses marked advantages, for certain purposes, over paper which is not soft. For instance, in the manufacture of bags and of paper to be wrapped around electrical conductors or other parts of electrical apparatus for insulating purposes, the paper should be soft and pliable. Furthermore, paper softened in accordance with the apparatus disclosed in my patents can be used in the manufacture of imitation leather. Where an effect simulating the appearance of alligator's skin is desired, the paper is subjected to the action of reversely inclined ribbing bars. In both of my patents hereinbefore referred to, the paper is passed through kneading rolls by means of which it is softened and, in the case of multi-layer

30 paper, the layers are loosened from each other at numerous points. Then, by the action of the ribbing bars, the various blister-like protuberances which have been formed by the action of the kneading rolls are folded down upon the other layer or layers and thus formed into ribs or ridges. By reversely inclining the ribbing bars, the ribs or ridges are caused to cross each other to produce the appearance of alligator skin, as hereinbefore explained.

The invention in this case relates more particularly to the feeding and ribbing devices and has for its object to improve the construction and operation of such devices and the condition of the paper as finally delivered from the apparatus.

More limitedly, the invention consists in providing each ribbing bar with means for positively feeding the paper in proper relation thereto; also in a particularly efficient form and construction of ribbing devices;

also in an effective arrangement of feeding and softening devices.

Generally speaking, the invention may be defined as consisting of the combinations of elements embodied in the claims hereto annexed and illustrated in the drawings forming part hereof, wherein

Figure 1 represents a side view of the complete apparatus, a portion of the main frame being broken away; Fig. 2 represents a sectional elevation of one set of ribbing bars, together with the coöperating feed and idle rollers by means of which the paper is supplied to and fed in contact with said ribbing bars, the view corresponding to the line 2—2, Fig. 1; Fig. 3 represents a side elevation of the apparatus shown in the preceding figures; Fig. 4 represents a detail in elevation of the mechanism shown at the left-hand end of Fig. 2; Fig. 5 represents a sectional detail corresponding to line 5—5 of Fig. 2 looking in the direction of the arrows; Fig. 6 represents an enlarged sectional detail of one set of ribbing rollers taken on the line 6—6 of Fig. 7, the rollers being shown in elevation; Fig. 7 represents a sectional detail corresponding to the line 7—7 of Fig. 6 looking in the direction of the arrows; Fig. 8 represents a similar view corresponding to line 8—8 of Fig. 6, looking in the direction of the arrows; Fig. 9 is a diagrammatic perspective view illustrating the manner in which the paper is subjected to the action of the ribbing mechanism; Fig. 10 is a top plan view of the first series of ribbing devices, showing a part of the second set; and Fig. 11 is a sectional detail taken on line 11—11 of Fig. 2.

Describing the parts in detail, 1 represents a suitable base on which are mounted a pair of side frames 2 by which the kneading rolls are supported. These frames may be provided each with a forwardly projecting bracket 3 supporting the roll of paper 4. The kneading or breaking rolls are designated by 5 and 6, the former rolls being the upper rolls and being mounted in vertically adjustable bearings 7, so as to vary the extent to which the blades 8 of the two rolls intermesh. These blades extend longitudinally of the rolls 5 and 6 and, as in the case of the construction shown in my patents aforesaid, the extent of such intermeshing will increase progressively from the first to the last set of rolls in the series.

9 denotes a guide roller or idler beneath

which the paper passes from the roll 4 and from which it passes between guide rollers having gears 10, said guide rollers being located in front of the first set of kneading 5 rollers.

11 denotes an idler interposed between the kneading rollers and the feed rollers 12, 13, which are located directly at the rear of the kneading rollers and by means of which the 10 paper is fed through the kneading rollers at a greater peripheral speed than the peripheral speed of said rollers, as explained in my Patent 873,169. The lower feeding roller 12 of each set is driven from a shaft 15 14 and the kneading rollers are driven from the lower feeding rollers by means of the gears 15, 16, 17, 18, 19, 10 and 20, as explained in my Patent 873,169. The upper 20 feed roller 13 of each set is mounted in a vertically adjustable bearing 21. Suitable 25 idle rollers 22, 23, 24, and 25 and guide rollers 26 and 27 are provided which are so positioned as to direct the paper properly to the kneading rollers and to the feed rollers.

25 In the drawings, I have shown one vertical series of kneading rollers and feeding rollers for purposes of illustration. It will be apparent that any suitable number of such series may be employed, according to 30 the circumstances of the particular case.

At the rear of the base, there are supported a suitable number of side frames 28 and 29. Between each pair of side frames there is mounted a pair of ribbing devices, 35 also suitable guide rollers for directing the paper in proper relation to the ribbing devices; also feed rollers, by means of which the paper is efficiently fed from one ribbing device to another.

40 Each set of ribbing devices comprises three rollers, with a triangular rib arranged therebetween, one of said rollers being a drive roller coöperating with the other rollers to drive the latter and hold the paper 45 against the edge of the ribbing bar and assist in feeding the paper thereacross. The first pair of side frames also has a pair of transverse kneading rollers at the top thereof by means of which the paper is further 50 softened before delivery to the first ribbing device, a vertically arranged idle roller and a pair of vertically arranged feeding rollers by means of which the paper is properly directed and positively fed from one ribbing 55 device to another; also a pair of transverse bottom feeding rollers, by means of which the paper is positively fed from the second ribbing device. In addition to the last-mentioned rollers, an idle roller may be employed to deliver the paper to a transverse 60 idle roller at the top of the next frame, whence it passes to the next series of ribbing devices. This second series may be similar to the first series and as many such series 65 as may be desirable or necessary will be em-

ployed. At the rear or delivery end of the apparatus, there is provided a pair of feed rollers, by means of which the paper will be finally discharged from the apparatus, being kept under tension by such last set of 70 rollers.

30 and 31 denote the transverse kneading rollers at the top of the first pair of side frames, from which the paper is delivered to the first ribbing device, which will now 75 be described in detail.

Each ribbing device comprises a ribbing bar 32, which is generally and preferably triangular in section and is interposed between three rollers 33, 34 and 35. The first 80 roller is the drive roller for the set and is provided at its outer end with a bevel gear 36 by means of which it is driven from a suitable drive shaft 37 through a bevel gear 38. Roller 33 is provided with a gear 39 85 meshing with similar gears 40 and 41 on rollers 34 and 35 respectively. Roller 33 is mounted in journals provided in the side frames 28. Rollers 34 and 35 are mounted respectively in journal boxes 42 and 43, 90 which journal boxes are reciprocable toward and from the axis of roller 33 as well as transversely to the lines joining the axes of the latter rollers and the axis of roller 33, as indicated in Figs. 7 and 8. Springs 44 95 and 45 are interposed between said journal boxes and roller 33 to yieldingly resist the adjustment of said journal boxes toward said roller and to move said boxes outwardly when the adjusting screws 46 and 47 are 100 slackened up. By means of screws 48 and 49, the journal boxes 42 and 43 and rollers 34 and 35 may be adjusted toward and from each other and toward and from the ribbing bar 32. This ribbing bar has its faces concaved to correspond in contour to the rollers 33, 34 and 35 and has its apex projecting between rollers 34 and 35. The entire ribbing device, comprising the three rollers and the ribbing bar, extends diagonally across 110 the side frames 29 forming an angle of 45 degrees with the top roller 31. The other ribbing device is also mounted at an angle of 45 degrees with respect to frame members 29 and top roller 31, but is oppositely inclined with respect to the former device. 115

The various rollers, including the vertical feed rollers are driven as follows: The rotation of the drive shaft 37 is transmitted by bevel gear 36 to roller 33 and, as previously 120 explained, by gear 39 on said roller to the gears on rollers 40 and 41. Shaft 37 is also provided with a gear 50 meshing with the gear 51 on a short shaft 52 which is provided at its inner end with a gear 53 meshing with the gear 54 on the transverse feed roller 55. Roller 55 is rotatably mounted on the shaft 56 and has on its neck a gear 57 which meshes with a similar gear on the neck of roller 58. Rollers 55 and 58 are the trans- 125 130

verse bottom feed rollers by means of which the tension on the paper from the rear ribbing device is maintained, and the paper is delivered from these rollers to a transverse 5 idle roller 59.

Shaft 56 is driven as follows: 60 denotes a short shaft having a pinion 61 at the inner end thereof and a gear 62 at the outer end. The last-named gear meshes with the gear 10 63 on shaft 56. The motion of shaft 56 is transmitted by a bevel gear 64 to the bevel gear 65 of the drive roller 66 of the next ribbing device. This ribbing device is identical 15 in construction with the ribbing device hereinbefore described and needs no detailed description. The only difference between the two ribbing devices is that the arrangement of rollers and ribbing bar is reversed with respect to the arrangement in the first set. 20 For instance, while in the first set the drive roller is on top and the driven rollers beneath, in the next set the drive roller 66 is beneath and the driven rollers 67 and 68 are on top. The ribbing bar will be correspondingly reversed, having its ribbing edge projecting upwardly between rollers 68 instead of downwardly. The paper, after having been fed to the first ribbing device, passes 25 around a vertically extending idle roller 69 mounted at one side of the frame and thence to the vertically extending feed rollers 70 and 71. Roller 70 is provided on its neck with a gear 72 adapted to mesh with a similar gear on roller 71 to drive the latter and is 30 also provided at its end with a bevel gear 73 which is driven as follows: Gear 53 on shaft 52 meshes with a gear 74 on a short transverse shaft 75 having at its outer end a bevel gear 76 meshing with bevel gear 73 on the 35 feed roller 70. By means of a chain 77 and suitable sprockets, a second shaft 37^a may be driven to operate in like manner the various corresponding rollers in the second side frames 29. The parts in the second side 40 frames are arranged in the same manner as in side frames 28 and need no detailed description. In the second frames, 78 denotes a transverse idle roller, which takes the place of the kneading rollers 30, 31 on the 45 first frame, 79 and 80 the bottom rollers of the first ribbing device, 81 and 82 the top rollers of the second ribbing device, 83 the bevel gear on the drive roller of the second ribbing device and 84 the bevel gear corresponding to the gear 64. 85 and 86 denote a 50 pair of feed rollers mounted at the bottom of frames 29 by means of which the paper is positively drawn from the last ribbing device. From rollers 85, 86, the paper is led 55 over idle roller 87 to the delivery feed rollers 88, 89 at the rear of the frames 29. These last rollers serve to keep the paper under such tension that it will always be tight 60 against the ribbing bars should any of the

intermediate rollers slip. The kneading 65 rollers 30, 31 are driven at a slower peripheral speed than the various feed rollers (which are all driven at the same rate of peripheral speed) in order to loosen and soften the paper in the manner explained in 70 my prior patents. Rollers 30, 31 may be conveniently driven from roller 70 by means of a bevel gear 90 on the shaft of the latter roller meshing with a bevel gear 91 on one end of a shaft 92 which is provided at its 75 opposite end with a bevel gear 93 meshing with a bevel gear 94 on the roller 31. The two rollers 31 are provided with intermeshing gears whereby one is driven from the other. With certain kinds of paper, the 80 rollers 30, 31 will soften and loosen the paper sufficiently without the necessity for the series of preliminary kneading rollers 5 and 6.

In operation, the paper designated by A is 85 drawn through each set of kneading rollers 5 and 6 by means of the feeding rolls 12 and 13, such kneading rollers loosening the layers 30 31, under the ribbing bar 32, in contact with rollers 33, 34 and 35 thence around 90 idle rollers 69 at the side of the frame, thence between feed rollers 70 and 71 to the second ribbing device, whence it passes in contact with the upwardly directed edge of the ribbing bar of this device and between 100 the rollers 66, 67 and 68, thence downwardly to feeding rollers 55 and 58, thence around idle roller 59, up over roller 78, and in similar manner to the ribbing devices in the second series, being fed from the last series or 105 set of ribbing devices by means of the feed rollers 85 and 86 located at the bottom of the apparatus. In passing through each series of ribbing devices, the paper is operated upon opposite sides thereof by the ribbing 110 bars of each series.

In Fig. 9 the paper web A is shown in the positions which it assumes in passing through the first series of ribbing devices. At the place designated *a*, it passes between the 115 kneading rollers 31; at *c* it passes around the first inclined ribbing bar, at *d* around roller 69, at *e* between rollers 70 and 71, at *f* around the second inclined ribbing bar, at *g* between feed rollers 55 and 58 and at *h* 120 around idle roller 59. In passing through the first series of ribbing devices the paper is reversed, so that in passing through the two series of devices, both sides of the paper are twice subjected to the folding action, 125 producing therein ribs or ridges, which ribs or ridges, with the inclined arrangement of the ribbing bars, cross each other to produce

a fair imitation of alligator skin. The use of the rollers in conjunction with the ribbing bars is a decided advantage, as it directs the paper properly across the edges of the ribbing bars and positively draws the paper across the edges of such bars by the application of the tractive force thereto in close proximity to such bars. Owing to the shortness of the web between the ribbing bars and the lines at which the paper is gripped by the rollers, considerable force may be applied to the paper without liability of tearing the same. The adjustability of the two driven rollers assures the meshing of the gear teeth thereon with the gear teeth on the driving roller and enables the paper to be operated upon in the most advantageous manner by the ribbing bars, especially when operating upon an uneven sheet of paper. Under certain conditions, the rollers associated with the ribbing bars need not be in such close proximity as to grip the paper therebetween. For instance, in operating upon light paper, there is no necessity for having the rollers actually grip the paper; in operating upon heavy paper, however, the rollers should grip and positively feed the paper. The adjustability of the bearings of the driven rollers enables them to be readily accommodated to the particular kind of paper being operated upon.

Having described my invention, I claim:

1. In an apparatus for softening paper, the combination of a series of ribbing bars, 35 rollers located on opposite sides of each bar, and means for feeding paper from one of said rollers to the other and across the edge of the interposed bar and from the last mentioned bar to the rollers at the next bar of 40 the series.

2. In an apparatus for softening paper, the combination of a ribbing bar, rollers located on opposite sides of said bar, and means for feeding paper from one of said 45 rollers to the other and across the edge of the interposed bar.

3. In an apparatus for softening paper, in combination, a ribbing bar, a roller at the back of said bar, a pair of rollers located on 50 opposite sides of the edge of said bar, means for driving the first mentioned roller, and a driving connection between said roller and the other two rollers.

4. In an apparatus for softening paper, in 55 combination, a ribbing bar, a roller at the back of said bar, a pair of rollers located on opposite sides of the edge of said bar, means for driving the first mentioned roller, a driving connection between said roller and the other two rollers, and means for adjusting 60 the latter rollers.

5. In an apparatus for softening paper, in 65 combination, means for loosening portions of multi-layer paper, ribbing bars for receiving the paper from said loosening means, and

feed rollers associated with each of said ribbing bars.

6. In an apparatus for softening paper, in combination, a series of oppositely inclined ribbing bars, means for loosening portions of 70 the layers of multi-layer paper, and rollers associated with each of said ribbing bars.

7. In an apparatus for softening paper, in combination, means for loosening portions of multi-layer paper, a pair of inclined ribbing 75 bars, rollers for directing the softened paper to said ribbing bars, and a vertically extending roller operatively interposed between said ribbing bars.

8. In an apparatus for softening paper, in combination, a frame, a pair of oppositely inclined ribbing bars supported in said frame, means for directing paper to one of said bars, and a pair of vertically extending feed 80 rollers mounted in said frame and operatively interposed between said bars.

9. In an apparatus for softening paper, in combination, a frame having a series of stationary ribbing bars, and feeding rollers associated with each of said bars and arranged 90 to feed the paper thereacross.

10. In an apparatus for softening paper, in combination, a ribbing bar, and rollers on opposite sides of said bar arranged to direct the paper thereacross, means for adjusting 95 said rollers with reference to said bar, and means for feeding the paper from one of said rollers to the other across the edge of the bar.

11. In an apparatus for softening paper, in combination, a frame, a pair of oppositely inclined ribbing bars extending diagonally 100 of said frame from side to side thereof, a pair of vertically extending feed rollers at one side of said frame, and a pair of feed rollers extending transversely of said frame. 105

12. In an apparatus for softening paper, in combination, a frame having at one end thereof a pair of kneading rollers, a pair of oppositely inclined ribbing bars supported by said frame, a pair of vertically extending feed rollers at one side of said frame, and a pair of feed rollers extending transversely of said frame and located at the opposite end of said frame from the first mentioned 110 rollers.

13. In an apparatus for softening paper, in combination, means for loosening portions of the layers of multi-layer paper, a pair of oppositely inclined ribbing bars, a vertical roller operatively interposed between said 115 ribbing bars, and a pair of transverse feed rollers located beyond the second ribbing bar.

14. A ribbing device comprising a drive roller, a pair of feed rollers, a ribbing bar mounted in the space between said rollers, and connections for driving said feed rollers from the drive roller. 125

15. In a ribbing device, the combination of a ribbing bar having an operating edge, a feed roller mounted on each side of said edge, 130

- a drive roller mounted at the back of said ribbing bar, and connections for driving the feed rollers from the drive roller. 65
16. The combination, with a ribbing device comprising a ribbing bar having an operating edge and a roller located on each side of said edge, of means for supplying paper from one of said rollers to the other and across the edge of the bar, and means for varying the positions of said rollers with respect to said bar. 70
17. The combination, with a ribbing device comprising a pair of rollers and a ribbing bar having an edge projecting into the space between said rollers, of means for adjusting said rollers toward and from said bar, and means for supplying paper from one of said rollers to the other and across the edge of said bar. 75
- 20 18. In a ribbing device, the combination of a drive roller and a pair of driven rollers grouped around a common center, a ribbing bar in the central portion of the space between said rollers and having its operating edge extending between the driven rollers, connections for driving the latter rollers from the drive roller, and means for adjusting said rollers toward and from the drive roller. 80
- 30 19. In a ribbing device, the combination of a drive roller and a pair of driven rollers arranged in a triangular group, with the drive roller at the apex of the triangle, a ribbing bar in the space between said rollers and having its edge projecting toward the base of the triangle and between the driven rollers, connections for driving the latter rollers from the drive roller, and means for adjusting the latter rollers toward the drive roller and toward each other. 85
- 40 20. In an apparatus for softening paper, the combination of a pair of side frames, an inclined ribbing bar extending therebetween, and an inclined roller arranged on each side of said bar and extending between said side frames. 90
- 45 21. In an apparatus for softening paper, the combination of a pair of oppositely located side frames and a pair of oppositely inclined ribbing bars, each bar having its opposite ends supported by opposite frames. 95
- 50 22. In an apparatus for softening paper, in combination, a series of oppositely inclined ribbing bars, means associated with each bar for supplying paper thereacross, rollers for feeding the paper through said series, a second series of oppositely inclined ribbing bars, and rollers for feeding paper across the second series of ribbing bars. 100
- 60 23. In an apparatus for softening multi-layer paper, the combination, with means for loosening portions of said multi-layer paper, of series of ribbing devices, each series comprising oppositely-inclined ribbing bars, and transverse and vertical feed rollers for feeding paper through each series of ribbing devices. 105
24. In an apparatus for softening paper, the combination, with means for loosening portions of multi-layer paper, of means for producing ribs or ridges in said paper, said means comprising rollers arranged at right angles to each other, a pair of oppositely inclined ribbing bars extending at an angle of 45 degrees with respect to said rollers, and means for feeding the paper from the last ribbing bar of the series. 110
25. In a ribbing device, the combination of rollers arranged in a triangular group, a ribbing bar in the space between said rollers and having its operating edge projecting between two of said rollers, and means for driving said rollers. 115
26. In a ribbing device, the combination of rollers arranged in a triangular group, a ribbing bar in the space between said rollers and having its operating edge projecting between two of said rollers, means for driving two of said rollers from one of said rollers, and means for adjusting the driven rollers. 120
27. In an apparatus for softening paper, in combination, means for loosening portions of multi-layer paper, a pair of inclined ribbing bars, rollers for directing the softened paper to said ribbing bars, a vertically extending roller operatively interposed between said ribbing bars and feed rollers additional to the first mentioned rollers. 125
28. In an apparatus for softening paper, in combination, a frame, a pair of inclined ribbing bars extending diagonally of said frame from side to side thereof, a pair of vertically extending feed rollers at one side of said frame, and a pair of feed rollers extending transversely of said frame. 130
29. In an apparatus for softening paper, in combination, a frame having at one end thereof a pair of kneading rollers, a pair of inclined ribbing bars supported by said frame, a pair of vertically extending feed rollers at one side of said frame, and a pair of feed rollers extending transversely of said frame and located at the opposite end of said frame from the first mentioned rollers. 135
30. In an apparatus for softening paper, in combination, means for loosening portions of the layers of multi-layer paper, a pair of inclined ribbing bars, a vertical roller operatively interposed between said ribbing bars, and a pair of transverse feed rollers located beyond the second ribbing bar. 140
